UNITED STATES PATENT OFFICE.

MARCEL H. TISNE, OF NEW YORK, N. Y., ASSIGNOR TO A. SCHRAADER'S SON, INCORPORATED, OF NEW YORK, N. Y., A CORPORATION OF NEW YORK.

HOLDER AND ATTACHER FOR FEATHERS.

1,077,653.

Specification of Letters Patent.

Patented Nov. 4, 1913.

Application filed August 3, 1912. Serial No. 713,054.

To all whom it may concern:

Be it known that I, MARCEL H. TISNE, a citizen of the United States, residing in the borough of Manhattan, city, county, and State of New York, have invented certain new and useful Improvements in Holders and Attachers for Feathers, of which the following is a specification.

This invention relates to improved means for attaching feathers to hats or the like, which is adapted also to be utilized for holding one or more feathers or plumes.

The usual method of attaching feathers or plumes is to provide a pliable length of wire to the quill end of the feather or plume, by either wrapping the wire around the feather or by binding it thereto with a thread. This method is also followed in the attachment of built-up plumes, the lower ends of the plumes being superposed and being connected to the wire in one or the other of the above ways. This method is, however, expensive, in that it involves hand labor and consumes considerable time for each feather or plume.

The object of the present invention is to provide a holder and attacher of cheap and simple construction which can be quickly applied to a feather or plume, or a group of the same, and which will securely hold the latter.

In its preferred form the invention comprises an elongated cup preferably having a conical lower end, to which is attached a length of pliable wire, the cup being adapted to be contracted about the stem or stems of the feathers so that the latter are finally united to the attaching wire.

In the drawings, which illustrate one form 40 of the invention Figure 1 is a side elevation of a plume showing the improved device in connection therewith. Fig. 2 is a longitudinal section of Fig. 1. Fig. 3 is a diagrammatic view illustrating the process of contracting the holder about the stem of the feather. Figs. 4 and 5 are side and edge views of a modified form of the attaching device.

Referring to the drawings, let A indicate 50 a plume which is shown as built up of several individual feathers, which are superposed so that their quill ends or stems B lie close together. According to the present invention the ends B are confined within a 55 holder C which, as shown, preferably com-

prises a cup-shaped member formed of brass or copper or other suitable metal which is adapted to be readily contracted. The member C is shown as elongated and having a conical lower end D, which constitutes the bottom of the cup. The member C is formed by a series of drawing operations, and during the process of manufacture is provided at its conical end with an aperture E which is designed to receive the upper end of the wire F. The wire F is formed of a pliable or flexible metal and is designed to be bent to any suitable shape to best permit the application of the feather or plume to the hat or other article to which it is to be attached. For this purpose it is made of considerable length and of sufficient diameter and strength to adequately support the feather or plume when the wire is sewed to the crown or brim of the hat. At the upper end of the wire F it is preferably provided with a collar G which is adapted to contact with the lower or conical end of the cup C, the wire beyond the collar extending into the interior of the cup and being there upset or riveted, as shown, to properly fasten the parts together. Preferably a drop or two of solder will be placed over the riveted end of the wire, as illustrated in Fig. 2, in order to secure a more rigid connection.

In the construction of the wire F a plain wire is preferably used, the collar or shoulder being formed by upsetting, sufficient metal being left beyond the collar to extend within the cup and secure the necessary rigid connection. When the stems of the feathers or plumes are inserted within the cup, the latter is then contracted to firmly grip the stems, and for this purpose it is preferred to employ a contracting machine such as is illustrated, for instance, in Patent No. 758,195 to M. C. Schweinert and H. P. Kraft. With such a machine the diameter of the cup is reduced without crimping so that after the contracting operation the cup presents a smooth exterior surface. By this means the appearance of the holder is not marred, it even being possible to initially nickel-plate the holder without materially affecting the coating by the contracting operation.

The size of the cup C may be proportioned to the commercial sizes of the feathers upon which they are to be used, three or

four sizes being sufficient to include most, if not all, of the commercial sizes. In the case of built-up plumes the aggregation of stems may be roughly shaped into circular form, it being possible to fit them directly into the cup, the contraction of the latter being sufficient to hold the group in place. If desired, the contracting dies may be provided with small projections by which the cup is indented or creased as at I I at one or more points during the contracting operation. In Fig. 3 is shown diagrammatically four dies H which, when closed, constitute a complete circle, each die being provided with a projection I' for indenting the metal as just described.

Figs. 4 and 5 show a form of the attacher suitable for sewing to a hat or other thing to which feathers or plumes are to be attached. The body C of the holder is tubular as before, but instead of a wire being provided as the attaching means the metal of the holder is flattened to form a base or attaching plate J having holes formed through it so that it may be sewed to the hat body by sewing through these holes, or it may be attached by wires, staples or the like, which may pass through these or any suitable holes. As shown, the device is made by first forming a tube and then flattening the lower end portion of the tube to form the attaching plate J, after which the holes are drilled through this plate. The tubular holder is designed to be contracted upon the stem or quill of the feather in the manner already described, either with or without the introduction of creases such as shown at I in Figs. 1 and 3.

While the preferred construction of the invention has been shown and described, it is to be understood that various changes may be made therein without departing from the spirit of the invention.

What I claim is:

1. A feather holder and attacher comprising a cup adapted to be contracted about the

stem of a feather, and a pliable member connected with the cup by which the feather may be attached to a hat or the like.

2. A feather holder and attacher comprising a metal cup adapted to be contracted about the stem of a feather, and a pliable wire member connected to said cup. 50

3. A feather holder and attacher comprising a sheet metal cup having a conical lower end and adapted to be contracted about the stem of a feather, and a pliable wire connected to said conical end. 55

4. A feather holder and attacher comprising a sheet metal cup adapted to be contracted about the stem of a feather, and a pliable wire passing through said lower end and riveted thereto. 60

5. A feather holder and attacher comprising an elongated sheet metal cup having a conical lower end, an aperture at said lower end, a pliable wire having a collar contacting with said lower end and a portion extending within said cup and riveted down on the interior thereof. 65

6. A feather holder and attacher comprising an elongated cup of metal adapted to be contracted about the stem of a feather, having an attaching member at its base, adapted for attachment to a hat or the like. 70

7. A plume, comprising a feather, and a holder contracted on the quill of said feather, said holder having means for attaching the same to an object. 75

8. A plume, comprising a feather, and a holder contracted on the quill of said feather, said holder having a pliable piece of wire connected thereto by which the plume is adapted to be attached to an object. 80

In witness whereof, I have hereunto signed my name in the presence of two subscribing witnesses.

MARCEL H. TISNE.
